(57) **CLAIM**

The ornamental design for a vacuum hose attachment as shown and described.

DESCRIPTION

FIG. 1 is a top front side perspective view of a vacuum hose attachment showing my new design;

FIG. 2 is a front view of the vacuum hose attachment, a rear view being a mirror image thereof;

FIG. 3 is a top view of the vacuum hose attachment, a bottom view being identical;

FIG. 4 is a left side view of the vacuum hose attachment;

FIG. 5 is a right side view of the vacuum hose attachment; and,

FIG. 6 is a partial cut-away top view of the vacuum hose attachment.
